United States Patent Office

Des. 186,404

Patented Oct. 20, 1959

186,404

ROOM THERMOSTAT

Estel C. Raney, Fort Lauderdale, Fla., assignor to Ranco Incorporated, Columbus, Ohio, a corporation of Ohio

Application November 20, 1957, Serial No. 48,570

Term of patent 14 years

(Cl. D52—7)

Fig. 1.

Fig. 2.

Fig. 3.

Fig. 1 is a front elevational view of a room thermostat showing my new design; and

Fig. 2 is side view in elevation of the thermostat; and
Fig. 3 is a top plan view thereof.

The essential features of my design reside in the portion shown in full lines.

I claim:

The ornamental design for a room thermostat, as shown and described.
